UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

DRILLING TOOL

Application filed March 17, 1926. Serial No. 95,400.

This invention relates to drilling tools and more particularly to hand held drilling tools of the rotary type especially adapted to use with coal mining machines in drilling "shot" holes in the coal during or subsequent to the cutting of a kerf therein and preparatory to the "shooting" of the coal from the "solid".

In coal mining during or subsequent to the cutting of a kerf in the face of the coal by the coal cutting machine and preparatory to the "shooting" of the coal from the "solid", it is the usual practice to drill a series of "shot" holes in the coal. Explosives are then inserted in the "shot" holes and the coal shot from the "solid" in the usual manner. In certain instances, the drilling tools for drilling these "shot" holes are driven independently of the coal mining machine, thereby greatly increasing the installation cost by the necessity of laying out separate power lines to both the drilling tool and the mining machine. These drilling tools are usually self-contained mechanisms adapted to be held by the operator during an operation thereof and driven by separate air or electric motors and are necessarily cumbersome and unwieldy to operate, due to the inherent weight of such motors and their related parts.

A primary object of this invention is to provide a drilling tool especially adapted to use in drilling "shot" holes in the coal and which is driven directly from the mining machine driving motor, thereby substantially decreasing the dimensions and weight of the tool. Another object of this invention is to provide an improved rotary drilling tool driven from the cutting mechanism transmission means of a coal mining machine. Another object of this invention is to provide an improved rotary drilling tool, especially adapted to use in drilling "shot" holes in the coal and which is freely movable bodily in any direction with respect to its source of power and which is of exceedingly inexpensive, simple, and compact character. A still further object of this invention is to provide an improved hand held drilling tool having improved and simplified controlling and driving means therefor. Yet another object of this invention is to provide an improved drilling tool having improved flexible transmission means between the tool and the source of power. These and other objects of my invention will, however, subsequently more fully appear.

This invention in one of its aspects may comprise a drilling tool deriving its power through the transmission gearing for the cutting mechanism of a coal mining machine with which the drilling tool cooperates in the mining of the coal. More specifically, this invention may comprise a hand held rotary drilling tool having a power shaft connected in a socket formed in one of the transmission gears for the cutting mechanism of a mining machine and this shaft preferably drives the drilling tool through suitable controlling mechanism and a flexible transmission shaft, herein preferably in the form of a wire rope or cable housed within a suitable flexible metallic covering.

In the accompanying drawings I have shown for purposes of illustration one form which my invention may assume in practice.

In these drawings,

Fig. 1 is a side elevation of the cutting end of a mining machine with which my improved drilling tool is associated.

Fig. 2 is a diagrammatic view illustrating the operation of the improved drilling tool in a mine.

Fig. 3 is a central longitudinal sectional view through the improved drilling tool.

Fig. 4 is a central longitudinal sectional view through a portion of the improved transmission means for the drilling tool.

Fig. 5 is a vertical transverse sectional view taken substantially on line 5-5 of Fig. 1 illustrating a portion of the improved controlling mechanism.

Fig. 6 is a detail view of the driving ratchet mechanism.

In this illustrative construction I have shown a drilling tool of improved form generally designated 1 operatively connected, through a flexible transmission element 2, to the cutting end of a mining machine generally designated 3. The mining machine 3 may assume various forms, but for the purposes of illustration I have shown a mining machine of the type described in my copending application, Serial No. 6,477, filed Feb. 2, 1925. As the structure of this mining machine does not specifically enter into my invention, detailed illustration and description of the same is deemed unnecessary other than to state that an armature shaft 4 of a reversible motor, not shown, is provided and drives through transmission means, to be herein-after described, a usual driving sprocket 5.

which cooperates with the usual cutter bit carrying cutter chain 6 to drive the latter in a well known manner. As illustrated, the motor shaft 4 is adapted to have connected thereto by means of a manually operable gear clutch 7 a bevel pinion 8 which is meshed with a larger bevel gear 9 rotatable on an axis perpendicular to the axis of the motor shaft 4 and this gear 9 is journaled within suitably spaced alined ball bearings 10 carried within the machine frame. The bevel gear 9 has formed thereon a spur pinion 11 which meshes with a larger spur gear 12 journaled on bearings 13 suitably carried in the machine frame. As shown, the gear 12 is adapted to drive through a manually controlled gear clutch 14, as is clearly described in my co-pending application mentioned above, a cutter chain driving shaft 15, the latter being journaled at its opposite ends within alined ball bearings 16. The shaft has keyed thereto at its lower end at 17 the cutter chain driving sprocket 5. From the foregoing description it will be clearly evident that when the clutches 7 and 14 are connected, the cutter chain driving sprocket 5 is adapted to be driven from the mining machine motor, but this driving sprocket 5 may be disconnected from the transmission gearing 8, 9, 11, and 12 at will by means of the gear clutch 14.

In referring more particularly to the improved construction, that is to the drilling tool and the driving and controlling connections therefor, it will be observed that disposed within a vertical socket or bore 18 formed within the shaft supporting the gears 9 and 11 and secured thereto by a key 19 is a shaft 20. As shown, the upper end of the shaft 20 is provided with a flat disk-shaped portion or flange 21 having formed on the upper plane surface thereof, projecting ratchet teeth 22 which are adapted to cooperate with corresponding projecting ratchet teeth 23 formed on a circular flange 24 carried at the lower end of a shaft 25, the latter being splined, as at 26, in operative sliding relation to a spiral gear 27, arranged coaxially with the spur pinion 11 and having oppositely projecting hub portions 28 journaled respectively in ball bearings 29 carried within a casing or housing member 30, suitably secured by bolts 31 to the frame of the mining machine. The casing 30 is, in this instance, composed of two main parts held together by bolts 32 and is provided with a depending sleeve portion 33 which forms a support for the upper ball bearing 10 in which the gears 9 and 11 are journaled. In accordance with this invention, a coiled spring 34 encircles the shaft 25 and is interposed between the flange 24 and the lower hub portion of the spiral gear 27, and this spring normally tends to yieldably hold the ratchet teeth 22, 23 in interengaged relation. To release the engagement of the ratchet teeth 22, 23 an operating

lever 35 is provided, secured as by a transverse pin 36 to an actuating rod 37 slidably mounted in a bore 38 formed in a detachable cover plate 39 secured to the casing 30. Furthermore, the handle 35 has formed thereon a cam 40 which engages a cam surface 41 formed on the upper surface of the cover plate 39. As shown, the lower end of the rod 37 is provided with a circular flange 42 which engages an inwardly extending flange 43 formed on a member 44 threadedly connected, as at 45, to the upper end of the shaft 25. From the foregoing description, it will be obvious that when the operator rotates the handle 35 the cam 40 rides upwardly on the cam surface 41, thereby causing longitudinal upward movement of the rod 37 and the shaft 25, consequently releasing the interengagement of the ratchet teeth 22, 23. It is therefore evident that the gear 27 may be driven or remain idle at will during running of the transmission gears 9, 11, and 12 of the mining machine cutting mechanism. Meshing with the spiral gear 27 and disposed on an axis at right angles to the axis of the gear 27 is a spiral gear 46 having secured thereto, as by bolts 47, oppositely extending hub portions 48 and 49 journaled respectively in ball bearings 50 suitably carried within bores 51 formed within the opposite ends of the casing 30, closure members 52 and 53 closing these bores. Secured within the spiral gear 46 is a series of clutch disks 54 which are interleaved with a series of clutch disks 55 carried by a clutch member 56 journaled at its opposite ends in radial bearings 57 and thrust bearings 58 carried by the hub portions 48 and 49. Slidably mounted on the hub portion 49 is a clutch applying member 59 having projecting fingers 60 extending through apertures 61 formed in the member 49 and these fingers 60 engage certain of the series of clutch disks 54, 55. Encircling the hub portion 49 and engaging the actuating member 59 and an adjustable collar 62 is a coiled spring 63. This spring tends to constantly force the clutch disks 54, 55 together. For releasing the actuating member 59 is a shipper yoke 64 engaging a radial flange 64^a formed on the actuating member. The shipper yoke 64 is pivoted, as at 65, and is secured to a transversely disposed shaft 65^a suitably journaled in the casing 30. The outer end of the shaft 65^a has secured thereto an operating lever 66. It will therefore be evident that when the lever 66 is swung downwardly the shipper yoke 64 swings about its pivot and the clutch actuating member is slid longitudinally, thereby releasing the engagement of the clutch disks and compressing the coiled spring 63. It will also be obvious that by slipping the clutch disks 54, 55 the speed of rotation of the drilling tool may be varied and that when the cutting tool is overloaded the clutch disks 54, 55 may automatically slip.

- thereby preventing breakage of the parts. Splined as at 67 in operative sliding relation with the clutch member 56 is a rotatable transmission member or shaft 68 having formed thereon at its forward end an enlarged socket portion 69 within which the rear end of a flexible transmission element 70, herein preferably in the form of a spirally laid wire rope or cable, is suitably rigidly secured preferably by brazing. The element 70 is so arranged that application of the relative force to its rear end tends to wind it tighter rather than to unwind it during drilling. The forward end of the wire rope 70 is likewise rigidly secured within a socket 71 formed within a member 72 secured as by a transverse pin 73 to a member 74, the latter being threadedly connected, as at 75, to a tool driving shaft 76. The tool driving shaft 76 is journaled at its opposite ends in ball bearings 77 of the combined radial and thrust type suitably carried within a casing 78 of the drilling tool 1. In this instance the forward end of the shaft 76 has formed integral therewith a socket 78^a which is adapted to receive the shank of the usual auger cutting tool 79. It will herein be observed that suitably secured at one end within a bell-mouthed guide member or adapter 80, threadedly connected as at 81 to the cover member 52, is a tubular metallic armor or covering element 82 for the cable 70, herein preferably of flexibly jointed structure. The opposite end of the flexible covering member 82 is suitably secured within a bell-mouthed guiding member or adapter 83, the latter being threadedly connected as at 84 to the casing 78 of the drilling tool. As illustrated, the casing 78 of the drilling tool is provided with lateral lugs or ears 85 to which are pivotally connected as at 86 oppositely extending lateral handles 87, the latter having lugs or stop members 88 which are adapted to engage the sides of the casing 78 when the handles are in extended position. The handles may be folded inwardly against the sides of the casing 78, as indicated by dotted lines in Fig. 3, when the tool is not in use.
- In the use of my improved drilling tool, it will herein be noted that after the kerf has been cut in the coal by the mining machine, the clutch 14 is thrown out by the operator, disconnecting the cutter chain drive and the machine is then retracted from the face in a suitable manner to the position shown in Fig. 2. The operator then manipulates the handle 35, thereby causing the ratchet teeth 22, 23 to be forced into operative driving engagement by means of a coiled spring 34, thus causing the spiral gears 27 and 46 and consequently the flexible transmission element 70 to be rotated, the splined connection 67 permitting sliding movement between the transmission element 70 and the clutch member 56 as the wire rope 70 alternately shortens and lengthens under load. This alternate shortening and lengthening of the wire rope transmits a vibrating action to the auger cutting bit which is found to be advantageous under certain conditions. It will also be noted that during this operation the frictional engagement between the clutch disks 54, 55 may be interrupted or varied at will upon suitable manipulation of the lever 66. The operator then grasps the handles 87 and the auger cutting tool is suitably positioned with respect to the coal face and may be fed inwardly by the operator as the hole deepens. After a series of "shot" holes have been drilled in the coal, the operator throws out the engagement of the friction clutch disks 54, 55 by compressing the coiled spring 63. Due to the flexible wire rope 70 the drilling tool 1 may be located in any desired position with respect to the mining machine. It will herein also be noted that the ratchet teeth 22, 23 automatically prevent reverse drive of the spiral gears 27 and 46 upon reversal of the driving motor, consequently preventing the uncoiling and the resultant damaging of the wire rope 70 and its related parts. It will also be noted that if desired, the "shot" holes may be drilled in the coal during the cutting operation of the mining machine thereby decreasing the time consumed in breaking down the coal. These and other operations of the improved mechanism will be clearly apparent to those skilled in the art.
- As a result of this invention it will be noted that an improved drilling tool is provided which is driven from the transmission means of the cutting mechanism of the mining machine, thereby reducing the dimensions and weight of the drilling tool to a minimum. It will further be noted that an improved rotary drilling tool is provided which is of exceedingly simple, inexpensive, and compact character. These and other advantages of my invention will be clearly apparent to those skilled in the art.
- While I have in this application specifically described one form which my invention may assume in practice, it will be understood that this form of the same is shown for purposes of illustration and that the invention may be modified and embodied in various other forms without departing from its spirit or the scope of the appended claims.
- What I claim as new and desire to secure by Letters Patent is:
1. In a drilling tool, a power driving element adapted to be driven in opposite directions, cooperating gearing driven thereby, mechanism connecting said gearing with said driving element, said mechanism being automatically operative to prevent driving of said gearing when said driving element is driven in one direction, a transmission shaft, a clutch connecting said shaft with said gearing, a flexible transmission shaft driven by

said shaft, and a drilling tool driven by said flexible transmission shaft.

2. In a drilling tool, a power driving element, cooperating gearing driven thereby, a ratchet mechanism connecting said gearing with said driving element, a transmission shaft, a clutch connecting said gearing with said shaft, a flexible transmission shaft driven by said shaft, and a drilling tool driven by 10 said flexible transmission shaft.

3. In a drilling tool, a power driving element, cooperating gearing driven thereby, a ratchet mechanism for connecting said gearing with said driving element, means for rendering said ratchet mechanism inoperative, a transmission shaft, a clutch connecting said gearing with said transmission shaft, a flexible transmission shaft driven by said shaft, and a drilling tool driven by said flexible 20 transmission shaft.

4. In a drilling tool, a power driving element, cooperating gearing driven thereby, a ratchet mechanism for connecting said gearing with said driving element, manually operable cam means for rendering said ratchet mechanism inoperative, a transmission shaft, a clutch connecting said gearing with said transmission shaft, a flexible transmission element driven by said shaft, and a drilling tool 25 driven by said transmission element.

5. In a drilling tool, a power driving element, cooperating gearing driven thereby, a clutch connecting said gearing with said driving element, a transmission shaft connectible 35 in operative sliding relation with one of said gears, a clutch connecting said gearing with said shaft, a flexible transmission element driven by said shaft, and a drilling tool driven by said transmission element.

40 6. In a drilling tool, a power driving element rotatable in opposite directions, cooperating gearing driven thereby, a ratchet mechanism releasable at will during driving thereof connecting said gearing with said 45 driving element, said ratchet mechanism being adapted to slip when said driving element is rotated in one direction, a transmission shaft, a clutch connecting said gearing with said shaft, a flexible transmission element 50 driven by said shaft and adapted to rotate in only one direction, and a drilling tool driven by said transmission element.

7. In a drilling tool, a power driving element rotatable in opposite directions, cooperating gearing driven thereby, a ratchet mechanism releasable at will during driving thereof for connecting said gearing with said driving element, said ratchet mechanism being adapted to slip when said driving element 60 is rotated in one direction, a transmission shaft, a clutch connecting said gearing with said shaft, a transmission element driven by said shaft and adapted to rotate in only one direction, and a drilling tool driven by said 65 transmission element.

8. In a drilling tool, a power driving element rotatable in opposite directions, cooperating gearing driven thereby, a ratchet mechanism for connecting said gearing with said driving element, said ratchet mechanism 70 being adapted to slip when said driving element is rotated in one direction, means operable at will during driving of said ratchet mechanism for rendering said ratchet mechanism inoperative, a transmission shaft, a 75 clutch connecting said gearing with said shaft, a transmission element driven by said shaft and adapted to rotate in only one direction, and a drilling tool driven by said transmission element.

9. In a drilling tool, a power driving element rotatable in opposite directions, cooperating gearing driven thereby, a ratchet mechanism for connecting said gearing with said driving element, said ratchet mechanism 80 being adapted to slip when said driving element is rotated in one direction, means operable at will during driving of said ratchet mechanism for rendering said ratchet mechanism inoperative, a transmission shaft, a 85 clutch connecting said gearing with said shaft, a flexible transmission element driven by said shaft and adapted to rotate in only one direction, and a drilling tool driven by said transmission element.

10. In a drilling tool, a power driving element rotatable in opposite directions, cooperating gearing driven thereby, a ratchet mechanism for connecting said gearing with said driving element, said ratchet mechanism 90 being adapted to slip when said driving element is rotated in one direction, manually operable cam means for rendering said ratchet mechanism inoperative, a transmission shaft, a clutch connecting said gearing with said 95 shaft, a transmission element driven by said shaft, and a drilling tool driven by said transmission element.

11. In a drilling tool, a power driving element rotatable in opposite directions, cooperating gearing driven thereby, a ratchet mechanism for connecting said gearing with said driving element, said ratchet mechanism being adapted to slip when said driving element is driven in one direction, resilient means 110 for maintaining said ratchet mechanism in operative position, manually controllable means operable at will during driving of said ratchet mechanism for overcoming said resilient means to render said ratchet mechanism inoperative, a transmission shaft, a clutch connecting said gearing with said shaft, a transmission element driven by said shaft and adapted to rotate in only one direction, and a drilling tool driven by said 115 transmission element.

12. In a drilling tool, a driving element, spiral gearing driven thereby, a ratchet mechanism for connecting said driving element with one of the gears of said gearing, said 120

- mechanism comprising cooperating ratchet elements and a spring for forcing said elements together, manually operable cam means for separating said ratchet elements to render 5 said ratchet mechanism inoperative, a transmission shaft, a friction clutch for connecting said gearing to said shaft, a flexible transmission element driven by said shaft, and a drilling tool driven by said transmission element.
- 10 13. In a drilling tool, a power driven element rotatable in opposite directions, spiral gearing driven thereby, a ratchet mechanism for connecting said driving element with one 15 of the gears of said gearing, said ratchet mechanism being adapted to slip when said driving element is rotated in one direction and comprising cooperating ratchet elements and a spring for forcing said elements together, 20 manually operable cam means for separating said ratchet elements to render said ratchet mechanism inoperative, a transmission shaft, a friction clutch for connecting said gearing to said shaft, a flexible transmission element 25 driven by said shaft, and a drilling tool driven by said transmission element.
14. In a drilling tool, a power driving element, cooperating spiral gears driven thereby, a ratchet mechanism for connecting one 30 of said gears with said driving element, said ratchet mechanism comprising cooperating ratchet elements, a spring for forcing said elements together, one of said elements having operative sliding relation with one of 35 said gears, a transmission shaft, a clutch for connecting said gearing to said shaft, a flexible transmission element driven by said shaft, and a drilling tool driven by said transmission element.
- 40 15. In a drilling tool, a power driving element, cooperating spiral gears driven thereby, a ratchet mechanism for connecting one of said gears with said driving element, said ratchet mechanism comprising cooperat- 45 ing ratchet elements, a spring for forcing said elements together, one of said elements having operative sliding relation with one of said gears, means for rendering said ratchet mechanism inoperative, a transmission shaft,
- 50 a clutch for connecting said gearing to said shaft, a flexible transmission element driven by said shaft, and a drilling tool driven by said transmission element.
- 55 16. In a drilling tool, a power driving element, cooperating spiral gears driven thereby, a ratchet mechanism for connecting one of
- said gears with said driving element, said ratchet mechanism comprising cooperating ratchet elements, a spring for forcing said elements together, one of said elements having operative sliding relation with one of said gears, manually operable cam means for rendering said ratchet mechanism inoperative, a transmission shaft, a clutch for connecting said gearing to said shaft, a flexible transmission element driven by said shaft, and a drilling tool driven by said transmission element.
- 60 17. In a drilling tool, a power driving element rotatable in opposite directions, spiral gearing driven thereby, a ratchet mechanism for connecting one of the gears of said gearing with said driving element, said ratchet mechanism being adapted to slip when said driving element is rotated in one direction and comprising cooperating ratchet elements, a spring for forcing said ratchet elements together, one of said elements having operative sliding relation with one of said gears, a transmission shaft, a friction clutch 75 for connecting said shaft with said gearing, a flexible transmission element driven by said shaft, and a drilling tool driven by said transmission element.
- 80 18. In a drilling tool, a power driving element rotatable in opposite directions, spiral gearing driven thereby, a ratchet mechanism for connecting one of the gears of said gearing with said driving element, said ratchet mechanism being adapted to slip when said driving element is rotated in one direction and comprising cooperating ratchet elements, a spring for forcing said ratchet elements together, one of said elements having operative 85 sliding relation with one of said gears, means 90 for rendering said ratchet mechanism inoperative including means for forcing said ratchet elements apart, a transmission shaft, a friction clutch for connecting said shaft with said gearing, a flexible transmission element driven by said shaft, and a drilling tool driven by said transmission element.
- 95 19. In a drilling tool, a power driving element, cooperating gearing driven thereby, mechanism connecting said gearing with said driving element, a reciprocable transmission shaft, a clutch connecting said gearing with said shaft, a flexible transmission shaft fixed to and driven by said shaft, and a drilling tool driven by said flexible transmission shaft.
- 100 In testimony whereof I affix my signature.
- MORRIS P. HOLMES.
